UNITED STATES PATENT OFFICE

WILLIAM E. WHITEHEAD, OF MILES PLATTING, ENGLAND, AND ABEL T. ATHERTON, OF LOWELL, MASSACHUSETTS.

IMPROVEMENT IN COTTON-OPENERS.

Specification forming part of Letters Patent No. 146,795, dated January 27, 1874; application filed October 3, 1872.

To all whom it may concern:

Be it known that we, WILLIAM E. WHITEHEAD, of Miles Platting, in the county of Lancaster, England, and ABEL T. ATHERTON, of Lowell, in the county of Middlesex and Commonwealth of Massachusetts, have invented certain Improvements in Cotton Openers, Scutchers, Lappers, &c., of which the following is a specification:

Our invention consists in the employment of a cylinder on a cotton-opener, &c., constructed either of rings or their equivalents, and having attached to their peripheries one or more plain angle-plates, and one or more toothed angle-plates, or said peripheries being covered exclusively with plain angle-plates, these plates being constructed in such a manner as to impart to the cylinder great strength and effectiveness in opening and cleaning cotton. Our invention further consists in the manner of attaching the sheet-iron covering to the cylinder.

The accompanying drawings represent our invention.

Figure 1 is a general section of the machine. Fig. 2 is a section through the adjustable bearing. Fig. 3 is a section across the adjustable bearing. Fig. 4 is a section in the line C D, Fig. 1, showing the movable bars. Fig. 5 is a portion of one of the toothed angle-plates. Fig. 6 is a portion of one of the plain angle-plates. Fig. 7 is a section of a portion of the cylinder, showing the slots in the plates and the sheet-iron covering-pieces inserted therein. Fig. 8 is a section in the line A B, Fig. 1. Fig. 9 is a section across the adjustable bearing in modified form.

H is a cylinder, composed wholly of a series of flat angle-plates, or with one or more toothed plates, attached to two or more rings, or their equivalents. This cylinder is strongly constructed, and is intended to open the cotton when taken directly from the bale, whereas, heretofore, it has been found necessary in most cases to put the cotton from the bale through another machine preparatory to its introduction into an opener. These plates, by being constructed in the angular form shown and described, possess great strength, and are easily and firmly attached to the cylinder-rings,

said rings having upon their peripheries recesses made to receive the plates. I I I are a series of movable longitudinal grid-bars, supported at each end, and moved by means of the rack G, operated by the cam P, to which is attached a chain-gear, said chain-gear being driven by a corresponding gear on the shaft of the cylinder X. K is one of two links, each connected at one end to the shaft of the cylinder X, and at the other end to the shaft of the adjustable swinging stripping-roll M. L is a slot in which the adjustable roll moves. M' is another stripping-roll, which operates in connection with the roll M. N represents a plain angle-plate, constructed with strong braces n, and showing upon its edges the grooves for the reception of the sheet-iron plates for covering the open spaces in the cylinder H. O is a toothed angle-plate, also strongly made. R is a spring, operating in connection with the movable bar-rack G, to return the bars to their places or proper position after having been moved by the cam P. S S are sheet-iron plates, which cover the spaces in the outside of the cylinder between the angle-plates, and which are inserted in the grooves shown in the edges of the angle-plates. T is a bushing, resting upon the rib V in the plate-box U, and held in its place by a setscrew, W, entering by its point into a countersunk hole in the top of the bushing. The rib is made by boring and counterboring the plate-box U.

Cylinders have been made before having flat blades attached to their surfaces; but, owing to the impossibility of firmly securing the same, they have been abandoned. Cylinders composed of blades with rows of teeth upon their surfaces, owing to the same difficulty of fastening, have also been abandoned.

Our blades are so constructed that all of the difficulties hereinbefore mentioned are removed.

In using some kinds of fibrous material, it may be advantageous to use a cylinder having a series of plain angle-plates upon its surface; and, under other circumstances, a cylinder-surface covered exclusively with toothed plates may be advantageously used; but we have found in working cotton that a cylinder-sur-

face composed of toothed and plain angle-plates is the most satisfactory, since the teeth soften the hard bunches of cotton, and loosen the leafy and other foreign matters connected with the cotton, while the plain angle-plates, following immediately after, remove the said foreign matters. By having the grid-bars move with a jarring motion, any dirt or other refuse matter lodging upon the bars is shaken off, and through the spaces between the same, so that all danger, in consequence of the dirt collecting and filling up the said spaces, and passing along with the cotton to the lap, is avoided. This bad result frequently happens when the grid-bars are stationary.

Owing to the great velocity at which the fan-shafts revolve, and the large amount of dirt from the cage-cylinders coming in contact with the same, as well as the liability of the floors settling, it has been found that a great amount of friction, and consequent wear of the boxes, and great expense in refitting, are the result, which is in a great measure obviated by the use of the bushing T, the same being very simple, and cheaply made, while, from the manner in which it is attached to the plate-box U, it is easily removed when worn out, and in case of any unevenness in the different parts of the machine, it adjusts and adapts itself thereto without increasing the amount of friction.

Fig. 9 shows a modification of the bushing as secured in the plate-box.

When the stripping-rolls are both stationary, if a large body of cotton passes between them, the gearing which drives the rolls is lia-

ble to be broken; whereas, by using an upper stripping-roll hung from the shaft of the top cage by means of links, as shown, the roll adjusts itself to any unevenness of the lap, and all danger of breaking the gearing is avoided, while its stripping functions remain unimpaired.

We have found by experience that when the sheet-iron covering attached to the cylinder is fastened to the ring by means of screws, the drilling and tapping of the rings necessary to admit the said screws renders the rings weak and more liable to break, while the edges of the sheet-iron are liable to become raised from the rings, and, by coming in contact with the cotton, are frequently torn from the cylinder, thereby causing disastrous results, which are entirely prevented by our construction, as represented, and herein described.

What we claim as our invention, and desire to secure by Letters Patent, is—

1. The beater-cylinder H, having the sheet-iron covering-plates S S applied to it, in the manner shown and described.

2. The beater-cylinder H, provided with plain angle-plates N N, constructed and arranged as and for the purpose herein specified.

3. The angle toothed plates O O, in combination with the plain angle-plates N N, all constructed as described, and for the purpose herein specified.

WILLIAM ED. WHITEHEAD.
